UNITED STATES PATENT OFFICE.

JOHN S. LAPP, OF LE ROY, NEW YORK, ASSIGNOR TO LAPP INSULATOR COMPANY, INC., A CORPORATION OF NEW YORK.

INSULATOR STACK.

Application filed May 19, 1927. Serial No. 192,509.

- This invention relates to insulators and more particularly to insulator posts or stacks such as are commonly employed for mounting outdoor switches, busses and the like.
- 5 Insulators of this type are generally formed by a plurality of units, each including a porcelain body portion having metal securing members in the form of metal flanges cemented to the top and bottom thereof. A number of these units are mounted one upon another, by securing the top flange of one unit to the bottom flange of the next superimposed unit, so as to form a stack or post of any desired size. It has hitherto been 10 difficult to properly align the various units of such a stack or pole, due to the fact that the metal flanges cannot be cemented to the porcelain with sufficient accuracy.
- An object of this invention is to provide a 20 device of the type set forth of such construction and arrangement that the parts thereof can be easily and quickly adjusted and properly positioned, irrespective of any inaccuracy in the union of the parts.
- 25 A further object is to provide a device for aligning the separate units of an insulator post, which will be simple in construction, effective in operation and easy and cheap to manufacture.
- 30 These and other objects which will be apparent to those skilled in this particular art are accomplished by means of the invention illustrated in the accompanying drawings, in which Figure 1 is a view in side elevation, 35 partly in section, of an insulator post constructed in accordance with one embodiment of this invention. Fig. 2 is a top plan view of one form of an adjusting shim or washer employed in the assembly shown in Fig. 1 and Fig. 3 is a side elevation thereof.
- The particular embodiment of this invention which has been chosen for the purposes of illustration consists of an insulator stack or post 5 which is formed in the usual manner by a plurality of superimposed insulator units 6 mounted one above the other to form a stack of any desired size. Each unit consists of a porcelain insulating member 7 having a metal connecting member 8 cemented 40 to the top thereof, and a lower metal connecting member 9 cemented to the bottom
- thereof. Obviously, the connecting members may be of any desired form. The parts are assembled by securing the lower connecting member of one unit to the upper member of another unit, and it will be apparent that any inaccuracy, however slight, in cementing the metal members to the porcelain body portion of each unit will result in such a misalignment of the units that the finished stack or 55 pole will not stand perpendicular upon its base.
- In order to permit the ready and accurate adjustment of the various parts in the field at the time the post is set up, the present invention includes the provision of sets of adjusting members or shims 10 between certain of the insulator units. Each member is in the form of an annular ring of beveled shape, as shown in Fig. 3. In the particular 60 embodiment which has been chosen for illustration, the annular ring is provided with slots 11 which cooperate with the securing bolts holding the adjacent units together so as to hold the rings in operative position 65 with relation to each other and to the associated units. It is, however, apparent that the slots 11 can be omitted and other forms of beveled cooperating shims employed. Each shim is also provided with a gripping 70 or striking lug 12 so that the two shims of a set can be rotated relatively to each other for the purpose of producing accurate alignment 75 of the various parts and for compensating for the misalignment resulting from the inaccuracy in securing the metal flanges to the porcelain body portions.
- 80 It will be found advantageous to use a pair of such adjusting members for approximately every five insulator units. Thus, for example, a stack of eight separate units would employ two sets of shims, one near the bottom and one near the top of the stack.
- 85 It will be readily apparent that rotation of one shim relatively to the other in any given pair will provide a micrometer adjustment of great delicacy which will permit the top of the stack to be accurately positioned as desired.
- 90 What I claim as new and desire to secure by Letters Patent is:
- 95 The combination in an insulator stack of

a plurality of insulator units including connecting members, fastening bolts for securing said members together, a pair of beveled adjusting shims positioned between two of 5 said members and having slots for receiving said bolts so as to permit relative rotation between said shims for varying the relative

positions of said units and means on said shims for causing relative rotation therebetween.

10

In testimony whereof, I have hereunto subscribed my name this 13th day of May, 1927.

JOHN S. LAPP.
